UNITED STATES PATENT OFFICE.

CHARLES HENRY KOFSKE, OF WATERLOO, IOWA.

BRAKE-BEAM.

979,968.

Specification of Letters Patent. Patented Dec. 27, 1910.

Application filed September 8, 1910. Serial No. 580,961.

To all whom it may concern:

Be it known that I, CHARLES H. KOFSKE, a citizen of the United States, residing at Waterloo, in the county of Blackhawk and State of Iowa, have invented certain new and useful Improvements in Brake-Beams; and I do declare the following to be a full, clear, and exact description of the invention, such as will enable others skilled in the art to which it appertains to make and use the same.

This invention relates to improvements in brake beams for railway rolling stock.

The object of the invention is to provide an improved brake beam which will be simple, strong and durable in construction, efficient and reliable in operation, light in weight and well adapted to the purpose for which it is designed.

With this and other objects in view, the invention consists of certain novel features of construction, combination and arrangement of parts as will be more fully described and particularly pointed out in the appended claim.

In the accompanying drawings: Figure 1 is a plan view of my improved brake beam; Fig. 2 is a rear view of the same; Fig. 3 is a vertical sectional view on the line 3—3 of Fig. 1; Fig. 4 is a similar view on the line 4—4 of Fig. 1; Fig. 5 is a detail view of the beam with the parts separated.

My improved brake beam comprises a lower metal plate or bar 1 which may be of any suitable size and has its opposite ends bent upwardly to form end flanges 2 as shown. Arranged above the bottom piece 1 and between the end flanges 2 is a top piece 3 said piece being also in the form of a flat metal plate. Between the bottom and top pieces 1 and 3 of the beam is arranged an intermediate piece 4 which is in the form of a metal plate constructed as shown whereby the same serves as a truss brace to prevent the bending or buckling of the brake beam when great strain is applied thereto. The ends of the bracing member 4 are enlarged as shown at 5 and closely engage or abut against the end flanges 2 of the beam whereby said bracing member is rigidly held when strain is applied to the beam. As hereinbefore described the bracing member 4 is formed in the shape of a truss brace or is formed at an angle on opposite sides of its center toward its ends. At the center of the member is formed a forwardly project-

ing tongue 6 which lies between the center of the upper and lower plates of the beam when the parts are assembled. The upper and lower plates and the truss brace are secured together midway between their ends by two bolts or rivets as shown.

Around the center of the upper and lower plates of the beam is arranged a clip 7 to which the brake operating lever is adapted to be connected. To the opposite ends of the beam are bolted or otherwise secured brake heads 8 on which are arranged brake shoes 9 of the usual or any desired construction. The brake beam adjacent to its opposite ends is also provided with guard pins 10 which are secured to the beam at their inner ends by a square headed bolt 10^a and an eye bolt 10^b as shown. The pins 10 are provided to prevent the beam from swinging out of position. The brake heads 8 have formed therein an aperture 11 and a notch 12 which are provided to receive different styles of hangers (not shown).

The brake heads 8 are preferably provided on their outer curved surfaces with laterally projecting lugs 11' through which are formed aligned apertures. The lugs 11' are adapted to engage in recesses 12' formed in the inner surfaces of the shoes 9. On the inner surface of the shoe 9 between the recesses 12' is formed a lug 13 provided with an aperture which, when the shoe is engaged with the head, is adapted to align with the apertures in the lugs on the head. When the shoe is thus engaged with the head a fastening pin or key 14 is inserted through aligned apertures in the lugs 11' and 13 thereby securely holding the shoe in place. The pin 14 is applied to the apertured lugs 11' and 13 through a groove or channel formed in the outer curved surface of the brake head.

A brake beam constructed in accordance with my invention will possess great strength and will be capable of resisting any strain placed upon the same in the application of the brake. The beam is supported by suitable supporting chains in the usual or any desired manner.

From the foregoing description taken in connection with the accompanying drawings the construction and operation of the invention will be readily understood without requiring a more extended explanation.

Various changes in the form, proportion and the minor details of construction may

be resorted to without departing from the principle or sacrificing any of the advantages of the invention as defined in the appended claim.

5 Having thus described my invention, what I claim is:

A brake beam comprising a lower plate having its opposite ends bent upwardly to form end flanges, an upper plate arranged 10 above said lower plate and between said flanges, a bracing member arranged between said plates and having its ends engaging the

end flanges of the bottom plate and a lever attaching clip arranged around the beam to hold said parts together in operative 15 position.

In testimony whereof I have hereunto set my hand in presence of two subscribing witnesses.

CHARLES HENRY KOFSKE.

Witnesses:

JOHN KOFSKE,
JOHN G. PENNIE.
